(57) **CLAIM**

The ornamental design for a display screen or portion thereof with animated graphical user interface, as shown and described.

DESCRIPTION

A portion of the disclosure of this patent document contains material to which a claim for copyright and/or trademark is made. The copyright and/or trademark owner has no objection to the reproduction of the patent document or the patent disclosure, as it appears in the U.S. Patent and Trademark Office records, but reserves all other copyright and/or trademark rights whatsoever.

The patent file contains at least one drawing executed in color. Copies of this patent with color drawings will be provided by the Office upon request and payment of the necessary fee.

FIG. 1 is a front view of a display screen or portion thereof with an animated graphical user interface showing a first image in a sequence showing our new design according to a first embodiment;

FIG. 2 is a second image thereof;

FIG. 3 is a front view of a display screen or portion thereof with an animated graphical user interface showing a first image in a sequence showing our new design according to a second embodiment; and,

FIG. 4 is a second image thereof.

The outer perimeter shown in dashed broken lines in the figures illustrates a display screen or portion thereof and forms no part of the claimed design. The remaining broken lines in the figures illustrate portions of the animated graphical user interface that form no part of the claimed design. The appearance of the image transitions sequentially between the images shown in FIGS. 1-2 and 3-4, respectively.
